UNITED STATES PATENT OFFICE.

CHRISTIAN PFEIFFER, OF NEW BRITAIN, CONNECTICUT, ASSIGNOR TO THE NEW BRITAIN HARDWARE MANUFACTURING CO., OF NEW BRITAIN, CONNECTICUT, A CORPORATION OF CONNECTICUT.

GOVERNOR.

SPECIFICATION forming part of Letters Patent No. 770,606, dated September 20, 1904.

Application filed March 2, 1904. Serial No. 196,210. (No model.)

To all whom it may concern:

Be it known that I, CHRISTIAN PFEIFFER, a citizen of the United States, residing at New Britain, in the county of Hartford, State of Connecticut, have invented certain new and useful Improvements in Governors, of which the following is a description, reference being had to the accompanying drawings and to the letters of reference marked thereon.

10 My invention relates to a combined automatic and manually actuated governor for spring-motors.

The objects of the invention are to provide a governor with a yieldingly-supported brake-block to act upon or be acted upon by the friction-disk of such governor; also, to form the said brake-block with a tapered working end to work in a correspondingly-formed annular groove in the friction-disk; also, to provide a 20 governor which shall be quick-acting and in which friction is reduced to a minimum; also, to provide a governor in which a very slow speed may be had at a uniform rate. These objects I attain by the construction shown in 25 the accompanying drawings, in which—

Figure 1 is a side elevation of a centrifugal governor having my improvement applied. Fig. 2 is a vertical sectional elevation thereof. Fig. 3 is a side elevation at right angles to 30 Fig. 1. Fig. 4 is a plan view.

A designates a suitable supporting-frame provided with upper and lower horizontally-extending brackets A' A² in vertical alinement. These brackets are in the form of split sleeves provided with clamping-screws a a', by means of which the bearing-blocks a' a' are adjustably but rigidly held in place.

G designates the governor of ordinary construction and mounted to slide upon the shaft 40 G', which bears at its ends on the bearing-blocks a' a'. The governor G is provided with the usual governor-balls or weighted arms g g, connected in the usual manner to the shaft G' and to the governor, so as to raise 45 and lower it on the shaft. The upper end of the governor G is provided with a friction-disk G³, having in its upper face an annular groove G⁴. The walls of this groove are bev-

eled or wedge-shaped, as shown, for a purpose to be presently described.

50 The shaft G' is provided with a worm or screw G² of very quick pitch, with which meshes a worm-gear E⁵ on a shaft E', geared in any suitable way to the motor or machine which is to be controlled as to its speed by the 55 governor.

The brake-block h, of suitable material—such as wood, leather, &c.—is beveled to correspond to the beveled groove G⁴, and is carried by the lower end of a tubular carrier h', 60 preferably provided with internal threads h² to securely hold the block h, and into the upper end of said carrier is screwed the lower end of the brake rod or stem h¹⁰. The carrier h' is mounted within the lower end of a tubular 65 plunger h³, reciprocating in a bearing h⁴, secured to the frame A, and in a bearing h⁵ in the upper bracket A' to one side of the upper bearing-block a'. The upper end of this tubular plunger h³ is slotted, as at H⁴, and into this 70 slot projects a pin extending through the brake rod or stem h¹⁰, so that the brake block and stem will rise with the tubular plunger and yet have independent vertical movement.

The interior of the tubular plunger h³ is in 75 two diameters, so that a shoulder h¹¹ is formed, and a spiral spring h⁹ is coiled around the stem h¹⁰ between this shoulder h¹¹ and the corresponding shoulder formed by the upper end of the carrier h'.

This spring h⁹ cushions the 80 upward movement of the brake-block, while a corresponding spring h¹² around the exterior of the tubular plunger h³ cushions its downward movement and also elevates it after each depression, or, in other words, acts to 85 keep said plunger elevated. This spring h¹² bears at its lower end on the bearing h⁴ and at its upper end on a split collar h⁶, clamped to the tubular plunger by a transverse screw h⁷, on the head end of which is mounted the 90 antifriction-roller h⁸.

H' designates a short horizontal rock-shaft mounted in bearings on the bracket A' and provided with a cam H, engaging the upper side of roller h⁸. The shaft H' is provided 95 with an operating-arm H³, clamped thereto,

as shown, and to the lower end of the arm is secured the end of a hand-operated rod H^4 by means of the adjustable collar h^3 . It will be seen, therefore, that the brake may be applied or adjusted toward disk G^3 at any time by simply pulling on the rod H^4 , which will cause cam H to depress collar h^6 and with it the tubular plunger h^8 , which through its shoulder h^{11} and spring h^9 will depress the carrier h' and its brake-block h , which latter will enter the beveled groove G^4 in the disk G^3 . Should the speed of the motor or machine become too great, the governor will automatically raise the disk G^3 and bring its friction-groove into engagement with the brake-block h . The use of the cushioning-spring h^9 allows of a very slow speed at a uniform rate. Moreover, the pitch of the worm or screw G^2 is much quicker or steeper than usual, and by it I reduce friction to a minimum and get a much quicker action. While a worm or screw having so steep a pitch is difficult to control, my construction of brake effects a perfect control thereof.

25 The collar h^6 serves as a stop for the brake device when the friction-disk is moved up automatically by the governor.

Having thus described my invention, what I claim, and desire to secure by Letters Patent, is—

30 1. The combination, with the governor-shaft and its disk, of a spring-controlled plunger, a spring-controlled brake-carrier mounted on the plunger to move independently thereof, and manually-actuated means acting on the plunger to move it any desired distance toward the disk; substantially as described.

35 2. The combination, with the governor-shaft and its disk, of a spring-controlled plunger, a 40 spring-controlled brake-carrier mounted on the plunger to move independently thereof, a cam acting on the plunger to move it any desired distance toward the disk, and means for actuating the cam; substantially as described.

45 3. The combination, with a governor-shaft and its friction-disk provided in one face with a beveled annular groove, of a spring-controlled plunger, an antifriction-roll thereon, a spring-pressed brake-carrier carried by the 50 said plunger, and movable independently thereof, a wedge-shaped brake-shoe on its carrier to engage said annular groove, a cam having a curved edge engaging said antifriction-roll, and means for operating the cam; substantially as described.

55 4. In a governor, the combination with the

governor-shaft and its friction-disk, of a spring-pressed carrier provided with a brake-block to engage the disk, a tubular plunger in which said carrier is slidably mounted and 60 means for operating the plunger.

5. In a governor, a brake mechanism comprising suitable bearings, a tubular plunger mounted thereon, means for raising and lowering the plunger, a brake-block carrier mounted 65 in the tubular plunger and a spring interposed between the plunger and carrier to cushion the movement of the carrier.

6. In a governor, a brake mechanism comprising a tubular plunger shouldered on the 70 inner side, a brake-carrier mounted in the plunger and provided with a stem, a pin-and-slot connection between the stem and plunger, and a spring on the stem between said shoulder and carrier.

7. In a governor, a brake mechanism comprising a tubular internally-shouldered plunger, a spring for retracting the plunger, means for projecting the plunger, a brake-carrier in the plunger provided with a stem 80 and having independent movement in the plunger, and a spring on the stem between the carrier and the plunger-shoulder.

8. In a governor, a brake mechanism comprising, a tubular internally-shouldered plunger, a spring for retracting the plunger, a cam for projecting the plunger, means for operating the cam, a brake-carrier in the plunger provided with a stem having a pin-and-slot connection with said plunger and a spring 90 on the stem between the plunger-shoulder and the brake-carrier.

9. In a governor, the combination with the governor-shaft and the governor-actuated friction-disk sliding thereon, of a brake mechanism comprising a tubular plunger having an internal shoulder, a collar on the plunger, a roller on the collar, a spring bearing on the collar to raise the plunger, a rock-shaft, a cam on the rock-shaft engaging said roller on said collar, an operating-rod connected with the rock-shaft, a brake-block carrier within the tubular plunger, a brake-block and a stem, there being a pin-and-slot connection between the stem, and plunger, and a spring on the 105 stem between said shoulder and the carrier.

In testimony whereof I affix my signature in presence of two witnesses.

CHRISTIAN PFEIFFER.
